FIG. 12

FIGURE 1 is a perspective view showing the front and one side of a cooker for frozen precooked food embodying my new design;

FIGURE 2 is a front elevational view thereof;

FIGURE 3 is a side elevational view thereof;

FIGURE 4 is a top plan view thereof;

FIGURE 5 is a rear elevational view thereof;

FIGURE 6 is a bottom view thereof;

FIGURE 7 is a perspective view of a modified form of the cooker for frozen precooked food shown in FIGURE 1;

FIGURE 8 is a front elevational view thereof;

FIGURE 9 is a side elevational view thereof;

FIGURE 10 is a top plan view thereof;

FIGURE 11 is a rear elevational view thereof; and

FIGURE 12 is a bottom view thereof.

The dominant features of my design reside in the portions shown in full lines. This application is a continuation of applications Ser. Nos. D. 78,886 and D. 78,889, filed Mar. 5, 1964, both now abandoned.

I claim:

The ornamental design for a cooker for frozen precooked food, as shown and described.
